UNITED STATES PATENT OFFICE.

ARTHUR AUBRIOT PONS, OF NEW YORK, N. Y.

ROWING-MACHINE.

1,013,437.

Specification of Letters Patent.

Patented Jan. 2, 1912.

Application filed February 8, 1911. Serial No. 607,336.

To all whom it may concern:

Be it known that I, ARTHUR AUBRIOT PONS, of Brooklyn, New York, in the State of New York, one of the United States of America, designer, have invented certain new and useful Improvements in Rowing-Machines; and I do hereby declare that the following is a full, clear, and exact description of the same.

The invention relates to improvements in rowing machines as described in the present specification and illustrated in the accompanying drawings that form part of the same.

5 The invention consists essentially in the novel construction and arrangement of parts, whereby the weight of the stroke is compensated by resilient elements attached to the seat and oar handles respectively in

10 a readily removable assemblage of parts. The objects of the invention are to provide an exercising machine of this type in which the operator can see at a glance the amount of exercise he has done, to provide 15 a machine with which exercise may be obtained for both body and arms simultaneously and generally to provide a rowing machine durable, portable, simple in construction, cheap to manufacture and whose 20 parts are readily accessible for renewal if necessary.

In the accompanying drawings Figure 1 is a perspective view of the machine and a portion of the wall and floor broken away. 25 Fig. 2 is a perspective view of a joint in the frame of the machine.

30 Like numerals of reference indicate corresponding parts in each of the figures.

Referring to the drawings; 1 is the base 35 frame of the machine, comprising longitudinal bars 2 and 3 and transverse bars 4 and 5 all preferably rectangular in cross section and joined together in any suitable manner but preferably by the well known 45 interlocking joint illustrated in Fig. 2. With the use of this joint the frame may be assembled or disassembled in a very short time as the said bars are not fastened together yet form a rigid frame when assembled.

50 6 are grooves cut in the outer side faces of the longitudinal bars 2 and 3 extending from the rear ends of said bars to a point intermediate of the length thereof.

7 and 8 are parallelly arranged axles, 55 upon the extremities of which are rotatably mounted the flanged wheels 9.

10 is a seat resting across the axles 7 and 8 and suitably clamped thereto on the underside, thus providing a sliding carriage 60 with flanged wheels adapted to roll along the longitudinal bars 2 and 3, the flanges retaining and guiding said carriage in its movement.

11 are curved arms rigidly secured to the 65 ends of the forward axles 7 outside of the wheels 9 and extending downwardly to the grooves 6.

12 are coiled springs lying within the 70 grooves 6 and having their one ends connected to the extremities of the curved arms 11, their other ends being secured to the ends of the longitudinal bars 2 and 3.

13 and 14 are rowing levers respectively 75 mounted upon the longitudinal bars 2 and 3 near the forward ends thereof, the outer ends of said levers being connected to said bars by ball and socket joints.

15 are hooks screwed into the levers 13 intermediate of the length thereof. 80

16 is an indicating device secured to the 85 wall of a building and 17 is a counting device arranged in the path of the finger 18 of said indicating device and operated each time said finger passes thereunder.

19 are springs having their one ends caught onto the hooks 15 and their other ends connected to a loop 20 forming a connection between said springs and the indicating device 16. 90

The indicating and counting devices have not been described in detail herein as the same form no part of this invention and any such devices may be used either separately or together. 95

21 are foot rests obliquely secured to the transverse bar 4 by the blocks 22.

23 are straps adapted to be secured over the feet of the operator to retain same on the foot rests 21. 100

In the use of this machine the operator sits upon the seat 11 with his feet held to the foot rests 21 by the straps 23. He then takes hold of the rowing levers 13 and pulls, with the result that the seat slides forward 105 through the wheels 9 rolling along the longitudinal bars 2 and 3 thereby stretching the springs 12 which provide a resistance to the

- forward movement of the seat. Simultaneously with the forward movement of the seat the rowing levers are pulled toward the operator the springs 19 being stretched and 5 providing a resistance to the movement of said levers, while the said springs being connected to the indicating device the finger 18 thereof will be moved over the dial, indicating the amount of the pull. Each time 10 the finger 18 passes the counting device 17 it will be recorded thereon so that the operator may see at a glance the exact amount of work he has done, namely the strength of the pull and the number of pulls.
- 15 One of the chief features of this machine is that the operator will obtain beneficial exercise both to the body and the arms, the springs 12 providing the necessary resistance for the former and the springs 19 for the 20 latter.
- 25 The details of construction may be modified to some extent so long as the main features are retained as set forth and claimed in the several claims for novelty hereinafter.
- 25 What I claim as my invention is:
1. In a rowing machine, a frame comprising longitudinal and transverse bars, a carriage 30 slideable on said longitudinal bars, means for resiliently resisting the sliding of said carriage in a forward direction, a pair of rowing levers mounted at the front of said longitudinal bars and means for resiliently resisting the rearward movement of said levers.
  - 35 2. In a rowing machine, a frame, a seat slideable on the rear end of said frame and spring held rearwardly, and a pair of rowing levers movably mounted on the forward end of said frame.
  - 40 3. In a rowing machine, a frame comprising detachable longitudinal and transverse bars, a pair of parallelly arranged axles, wheels 45 rotatably mounted on the ends of said axles and adapted to roll on said longitudinal bars, a seat mounted on said axles, means resiliently connecting one of said axles with the rear end of the frame, a pair of rowing levers pivotally mounted on the front end of said frame, an indicating device 50 rigidly secured to a stationary structure in front of the machine and springs con-

necting said indicating device with said rowing levers.

4. In a rowing machine, a frame comprising longitudinal and transverse bars detachably united, a pair of parallelly arranged axles, flanged wheels rotatably mounted at the ends of said axles and adapted to roll on said longitudinal bars, a seat mounted across said axles, curved arms rigidly secured to the ends of one of said axles, springs having their one ends secured to the curved arms aforesaid, and their other ends to the rear ends of said longitudinal bars, a pair of rowing levers mounted with ball and socket joints upon the front ends of said longitudinal bars respectively, an indicating device rigidly secured to a stationary structure in front of the machine and springs resiliently connecting said rowing levers with said indicating device.

5. In a rowing machine, a frame comprising longitudinal and transverse bars, said longitudinal bars having grooves in their outer side faces extending from the rear end toward the front thereof, a pair of parallelly arranged axles, flanged wheels rotatably mounted at the ends of said axles and adapted to roll on said longitudinal bars, a seat mounted upon said axles, curved arms extending downwardly from the ends of one of said axles, springs lying in said grooves and having their one ends secured to the curved arms aforesaid, and their other ends secured to the rear ends of the longitudinal bars, a pair of rowing levers mounted with ball and socket joints upon the front ends of the longitudinal bars respectively, an indicating device rigidly secured to a stationary structure in front of the machine, springs 80 resiliently connecting said rowing levers with said indicating device, and foot rests mounted upon one of the transverse bars aforesaid toward the front of the machine.

Signed at the borough of Brooklyn, New York, N. Y., U. S. A. this third day of February 1911.

ARTHUR AUBRIOT PONS.
